UNITED STATES PATENT OFFICE.

MICHAEL I. GINSBURG, OF PHILADELPHIA, PENNSYLVANIA.

WRENCH.

1,171,939.

Specification of Letters Patent. Patented Feb. 15, 1916.

Application filed March 18, 1914. Serial No. 825,718.

To all whom it may concern:

Be it known that I, MICHAEL I. GINSBURG, a citizen of the United States, residing at Philadelphia, in the county of Philadelphia and State of Pennsylvania, have invented new and useful Improvements in Wrenches, of which the following is a specification.

My invention relates to new and useful improvements in wrenches, and has for its object to provide an exceedingly simple and effective device of this character having an adjustable jaw, which may be readily adjusted upon the work in the ordinary manner, said adjustable jaw being so mounted as to coöperate with the work when said wrench is swung in one direction to turn said work, and also to slip freely around the work when the wrench is swung in the opposite direction.

20 A further object of the invention is to provide a wrench including an adjustable jaw provided with an adjusting means of the ordinary character which is slidable coincident with the jaw to permit the latter to move within certain limits, whereby the wrench may be turned without removing the same from the work in a manner similar to a ratchet wrench.

25 A still further object of the invention is to provide a wrench having a stationary jaw and an adjustable jaw, the latter being capable of adjustment in the ordinary manner, and the adjustable means being slidable with the adjustable jaw, but normally held in the direction which will force the adjustable jaw toward the stationary jaw, and having means controlled by the handle for locking or holding the adjustable jaw in its adjusted position.

40 With these ends in view, this invention consists in the details of construction and combination of elements hereinafter set forth and then specifically designated by the claims.

45 In order that those skilled in the art to which this invention appertains may understand how to make and use the same, I will describe its construction in detail, referring by numerals to the accompanying drawing forming a part of this specification, in which—

Figure 1, is a top edge view of a wrench made in accordance with my improvement. Fig. 2, is a central longitudinal section thereof, portions thereof being left in eleva-

tion to clearly illustrate the same; and Fig. 3, is a bottom edge view thereof.

In carrying out my invention as here embodied 2 represents the housing or head of the wrench having formed therewith the stationary jaw 3, and in this head is fitted the shank 4 of the movable jaw 5. On the inner edge of the shank is formed the teeth or sectional screw threads 6 with which meshes the adjusting screw 7. Said adjusting screw is journaled upon the spindle 8, one end of which is of greater diameter than the body to form a head 9 which produces a shoulder 10 adapted to engage one end of the adjusting screw 7. The head 9 of the spindle is slidably mounted in the hole 11, while the body 8 passes through a hole 12 in alinement with the hole 11, and the opposite end normally rests in the cavity 13 in which is situated the spring 14 coiled about the spindle 8, the latter having a nut 15 threaded on its end against which rests one end of the spring. The nut 15 is free to slide within the cavity 13. The spring 14 acting upon the nut 15 normally forces the spindle 8 outward, so that its head 9 draws the adjusting screw 7 toward the cavity 13, and since said adjusting screw is in mesh with the sectional threads on the shank of the adjustable jaw, said adjustable jaw is normally forced toward the stationary jaw 3 or the work on which the wrench is being used.

16 denotes the handle in the form of a lever pivoted at 17 within the head or housing, and one end is provided with a locking toe 18 which projects within the path of the adjusting screw 7 to lock the same against its sliding movement when the wrench is being used to turn the work home.

One edge of the handle is provided with a notch 19, the walls of which coact with the stop 20 carried by the housing to limit the movements of said handle. In the opposite edge of the handle 16 is set the spring 21 held in place by some suitable fastening means such as screws 22. The opposite or free end of said spring coacts with a portion of the head or housing to force the handle 16 in that direction which will bring the toe 18 into contact with the adjusting screw 7.

In practice the movable jaw is adjusted to the size of the nut or other work to be operated upon by the proper manipulation of

the adjusting screw 7, the spring 14 holding the jaws in a firm but yielding contact with the nut, when by pulling upon the handle 16, in that direction which will bring the 5 toe 18 into contact with the adjusting screw 7, said adjusting screw will be locked or held in its normal position, thus locking the adjustable jaw and preventing the same from moving lengthwise, and when all of 10 the parts are so locked, the wrench is operated in the usual manner.

By reversing the power on the handle 16, the toe 18 will be disengaged from the adjusting screw 7, thereby unlocking the latter, leaving only the pressure of the spring 14 to hold the movable jaw in contact with the work, and by further moving the handle 16 the same will cause the head to be moved, and as the movable jaw 5 contacts 20 with the edges or high parts of the nut, said movable jaw will be forced away from the work, and the adjusting means will slide coincident therewith against the action of the spring 14, giving it all the effects of a 25 ratchet wrench.

A wrench made in accordance with this description will perform all the functions of a number of other wrenches, such as the monkey wrench, the open end wrench and 30 the quick acting jaw wrench.

Of course I do not wish to be limited to the exact details of construction as herein shown, as these may be varied within the limits of the appended claims without departing from the spirit of my invention.

Having thus fully described my invention, what I claim as new and useful, is—

1. A wrench including an adjustable jaw, an adjusting means, a spring for normally 40 forcing the jaw toward the work through the medium of the adjusting means, said adjusting means being slidably coincident with the jaw, and a pivoted operating handle provided with means to coact with the 45 adjusting means for holding the adjustable jaw against the work.

2. A wrench including an adjustable jaw, an adjusting means, a spring for normally 50 forcing the jaw toward the work through the medium of the adjusting means, said adjusting means being slidable coincident with the jaw, a pivoted operating handle provided with means to coact with the adjusting means for holding the adjustable 55 jaw against the work, and means for limiting the reverse movement of the handle.

3. A wrench including an adjustable jaw, an adjusting means, a spring for normally 60 forcing the jaw toward the work through the medium of the adjusting means, said adjusting means being slidable coincident with the jaw, a pivoted operating handle provided with means to coact with the adjusting means for holding the adjustable 65 jaw against the work, means for limiting

the reverse movement of the handle, and a spring for normally forcing the handle toward its holding position.

4. In a device of the character stated a head provided with a stationary jaw, an 70 adjustable jaw provided with a shank, the inner edge of said shank being provided with sectional threads, an adjusting screw meshing with said sectional threads, a spindle on which the adjusting screw is journaled, said spindle being slidably mounted in the head and provided with an enlarged portion to form a shoulder for coacting with the adjusting screw, a jaw threaded on the opposite end of said spindle, a spring coiled 80 about said spindle, one end thereof resting against a portion of the head, and the other end resting against said nut for normally forcing the spindle outward and through the medium of the adjusting screw normally 85 forcing the adjustable jaw toward the stationary jaw, a handle pivoted within the head provided with a locking toe adapted to coact with one end of the adjusting screw and having a notch in one edge thereof, a 90 stop carried by the head and registering with said notch for limiting the movements of handle, and a spring carried by the handle and coacting with the head for normally 95 forcing the handle in that direction which will cause the locking toe to engage the adjusting screw.

5. A wrench including a head, provided with a stationary jaw, an adjustable jaw 100 slidably mounted in said head, an adjusting screw for adjusting said adjustable jaw, a spindle slidably mounted in the head, on which the adjusting screw is journaled, means for normally forcing the spindle outward to force the adjustable jaw toward the 105 stationary jaw through the medium of the adjusting screw, and a pivoted operating handle adapted to hold the adjustable jaw against the work through the medium of the 110 adjusting screw.

6. In a device of the character stated a head provided with a stationary jaw, an operating handle pivoted thereto, an adjustable jaw slidably mounted in the head, a spindle also slidably mounted in said head, 115 means for normally forcing said spindle outward, and an adjusting screw journaled on said spindle and coacting with the adjustable jaw, whereby the latter may be adjusted, said operating handle coacting with the adjusting screw to hold said adjustable jaw against pressure thereon.

7. A wrench comprising a head, a stationary jaw projecting from said head, an adjustable jaw slidably mounted in said 120 head, an adjusting means also slidably mounted in said head and coacting with the adjustable jaw for actuating the same toward or away from the stationary jaw, means for normally forcing said adjusting 125

means in that direction which will force the adjustable jaw toward the stationary jaw and thereby hold said adjusting means stationary with relation to the head while the 5 adjustable jaw is being adjusted and a pivoted operating handle provided with means for engagement with the adjusting means for holding the adjustable jaw against the work.

10 8. A wrench comprising a head, a stationary jaw projecting from said head, an adjustable jaw slidably mounted in said head, an adjusting means also slidably mounted in said head and coacting with the 15 adjustable jaw for actuating the same toward or away from the stationary jaw, a spring situated within the head and engaging a portion of the adjusting means for normally forcing said adjusting means in 20 that direction which will force the adjustable jaw toward the stationary jaw and thereby hold said adjusting means stationary with relation to the head while the adjustable jaw is being adjusted, and a 25 pivoted operating handle provided with a toe arranged to engage the adjusting means for holding the adjustable jaw against the work.

9. A wrench comprising a head, a stationary jaw projecting from said head, an adjustable jaw slidably mounted in said head, a rotatable adjusting means slidably mounted within the head and coacting with the adjustable jaw whereby the latter may

be adjusted when the adjusting means is 35 stationary with relation to the head, means for normally holding said adjusting means in said stationary position when no force is brought to bear upon the adjustable jaw, and a pivoted operating handle provided 40 with means for engaging the adjusting means for holding the adjustable jaw against the work.

10. A wrench comprising a head, a stationary jaw projecting from said head, an 45 adjustable jaw slidably mounted in said head, a rotatable adjusting means slidably mounted within the head and coacting with the adjustable jaw, whereby the latter may be adjusted when the adjusting means is 50 stationary with relation to the head, means for normally holding said adjusting means in said stationary position when no force is brought to bear upon the adjustable jaw, but having capacity to permit said adjusting means to slide co-incident with the adjustable jaw when force is brought to bear against said jaw, and a pivoted operating handle provided with means projecting 55 therefrom to engage said adjusting means to hold the latter in its normal stationary position and through the medium thereof to hold the adjustable jaw in a stationary position against the work.
